UNITED STATES PATENT OFFICE.

WILLIAM H. WOOD, OF SOUTH EUCLID, OHIO.

RESPIRATOR.

Application filed June 30, 1919. Serial No. 307,497.

To all whom it may concern:

Be it known that I, WILLIAM H. Wood, a citizen of the United States, residing at South Euclid, in the county of Cuyahoga and State of Ohio, have invented a certain new and useful Improvement in Respirators, of which the following is a full, clear, and exact description, reference being had to the accompanying drawings.

10 This invention relates to respirators, such as are employed for the purpose of preventing the inhalation of dust and other particles in suspension by operators in various industries. It is the general object of 15 the invention to provide a respirator of this character which is more efficient in operation than those in general use. Further and more limited advantages of the invention are to provide a respirator which is simple 20 and economical of production; which can be worn without discomfort; which will be capable of long-continued use; which may be conveniently assembled; and which will permit the easy removal and renewal of the 25 straining or collecting element.

I accomplish these objects in and through the construction and arrangement of parts illustrated in the drawings forming part hereof, wherein Fig. 1 represents a perspective view of an embodiment of my respirator showing its manner of use; Fig. 2 a 30 similar view of the separated component parts of the respirator; and Fig. 3 a vertical sectional view through the respirator.

35 The respirator shown herein comprises three parts, namely: a combined clamping and base member, a cooperating clamping member, and a straining or sediment-removing member or element adapted to be interposed between and clamped by the first 40 mentioned members in operative relation to the face of the wearer.

Describing the parts by reference characters, 1 denotes the combined base and 45 clamping member. This member may be made of any suitable rigid material and is so shaped as to engage and conform more or less closely at its base portion to the nose, cheeks and chin of the wearer, being provided with a central arch 2 at one end thereof for application to the nose. The member 1 is provided with an open-work supporting 50 frame for the straining element or member, the said frame projecting outwardly so as to sustain the said element at a suitable distance from the mouth and nose of the

wearer. This frame is shown as provided by a plurality of wires or light bars 3 forming projections on the frame and bent each in an inverted U-form, each having its ends 60 secured to the outer portion of the member 1. A second set of wires or light bars 4 are shown as extending at substantially right angles to the wires or bars 3 and connected in like manner to the member 1, the wires 65 or bars 3 and 4 forming an open-work frame for the straining element 5. This element may be of any pliable or yielding porous material such as gauze or light bath toweling, and is of sufficiently greater extent 70 than the exterior supporting surface provided by the parts 1, 3 and 4 to enable the edges 5^a to bear against and conform to the face of the wearer and provide a dust-excluding contact therewith.

75 Cooperating with the member 1 is the clamping member 6, which is of the same general contour as the member 1, the outer peripheral surface of the base of the member 1 and the inner surface of the member 6 being preferably beveled, whereby the application of the member 6 to the member 1 will result in clamping the element 5 therebetween. The member 6 is shown as provided with a pair of wires 7 pivoted to opposite sides thereof and each having a hook 8 adapted to be engaged behind an ear of the wearer.

80 The members 1 and 6 may be made of any light material such as aluminum or wood, and the complete device may be supported by the ears of the wearer, without the discomfort which is a necessary incident to the use of the ordinary, heavy respirator. The 85 construction and arrangement of parts is such that the edges of the straining element 5 lie snugly against the face of the wearer, thus preventing access of dust or other particles between such edges and the face.

90 When it is desired to replace the said element, it is necessary only to move the member 6 away from the member 1, which will permit the straining element to be removed from the latter member and to be sterilized 95 and re-used. The construction of the support for the straining element insures a maximum breathing surface, which adds materially to the comfort of the wearer. A further advantage of the invention resides 100 in the fact that the respirator may be used indefinitely, requiring only the renewal of 105 the straining element from time to time;

and, as pointed out, the straining element may be sterilized and re-used indefinitely.

Having thus described my invention, what I claim is:—

- 5 1. A respirator comprising a base member adapted to conform to the face of the wearer, said member having an outwardly inclined surface, an open-work supporting frame projecting outwardly from said member, a clamping member adapted to be applied to the inclined outer surface of the first mentioned member, a pliable strainer element adapted to be inserted between said members and to be supported upon said 10 frame, and means connected with the clamping member for supporting the respirator in operative relation to the face of the wearer.
- 15 2. In a respirator, the combination of a rigid base member adapted to conform to the face of a wearer and having its peripheral surface beveled outwardly toward its base, rods or wires secured to said base member and projecting outwardly therefrom to provide an open-work frame, a clamping member shaped to fit about said base member, a pliable strainer member extending over said frame and the inclined surface of the base member, and hooks pivoted to opposite sides of the clamping member.
- 20 3. In a respirator, the combination of a rigid base member, a clamping member, and a strainer member of pliable material, the base member and the clamping member being shaped so that, when connected, the marginal portion of the strainer member will be forced into dust-excluding direct contact with the face of a wearer, and means for securing together the base member, the strainer member, and the clamping member
- 25 35 and for supporting all of said members upon the face of the wearer.
- 40 4. A respirator comprising a rigid open base member shaped to conform to the face of a wearer and having an inclined outer surface; a strainer member of yielding material overlying said base member and adapted to be clamped between said base member and a clamping member in position to engage the face of the wearer; and an open clamping member having an inner surface complementary to the inclined outer surface of said base member, adapted to clamp said strainer member between itself and said base member in position to engage the face of the wearer, and of such size relative to said base member that in normal clamping position said clamping member is received upon said base member substantially to the face-engaging edge of said base member and is thereby effective to positively force said strainer member against the face of the wearer; and means for securing all of said members to the head of the wearer.
- 45 5. A respirator comprising a rigid open base member shaped to conform to the face of a wearer and having an inclined outer surface; a strainer member of yielding material overlying said base member and

surface; a strainer member of yielding material overlying said base member and adapted to be clamped between said base member and a clamping member in position to extend inwardly to engage the face of the wearer; and an open clamping member having an inner surface complementary to the inclined outer surface of said base member, adapted to clamp said strainer member between itself and said base member in position to extend inwardly to engage the face of the wearer, and of such size relative to said base member that in normal clamping position said clamping member is received upon said base member substantially to the face-engaging edge of said base member and is thereby effective to positively force said strainer member against the face of the wearer.

6. A respirator comprising an open base member shaped to conform to the face of a wearer; a strainer member of yielding material overlying said base member and adapted to be clamped between said base member and a clamping member in position to engage the face of a wearer; and an open clamping member having that edge adjacent the face of the wearer also shaped to conform to the face of the wearer, adapted to clamp said strainer member between itself and said base member in position to engage the face of the wearer, and adjustable upon said base member to permit cooperation between said clamping member and said base member to compensate for variations in the face of the wearer and thus cause said strainer member to closely engage the face of the wearer despite said variations.

7. A respirator comprising a rigid open base member shaped to conform to the face of a wearer and having an inclined outer surface; a strainer member of yielding material overlying said base member and adapted to be clamped between said base member and a clamping member in position to engage the face of the wearer; an open clamping member having an inner surface complementary to the inclined outer surface of said base member, adapted to clamp said strainer member between itself and said base member in position to engage the face of the wearer, and of such size relative to said base member that in normal clamping position said clamping member is received upon said base member substantially to the face-engaging edge of said base member and is thereby effective to positively force said strainer member against the face of the wearer; and means for securing all of said members to the head of the wearer.

8. A respirator comprising a rigid open base member shaped to conform to the face of a wearer and having an inclined outer surface; a strainer member of yielding material overlying said base member and

adapted to be clamped between said base member and a clamping member in position to extend inwardly to engage the face of the wearer; an open clamping member having 5 an inner surface complementary to the inclined outer surface of said base member, adapted to clamp said strainer member between itself and said base member in position to extend inwardly to engage the face 10 of the wearer, and of such size relative to said base member that in normal clamp- ing position said clamping member is received upon said base member substantially to the face-engaging edge of said base member and is thereby effective to positively 15 force said strainer member against the face of the wearer; and means for securing all of said members to the head of the wearer.

In testimony whereof, I hereunto affix my signature.

WILLIAM H. WOOD.
